UNITED STATES PATENT OFFICE

92,229

DESIGN FOR A LAMP

James H. Cannon, Los Angeles, Calif.

Application December 8, 1933, Serial No. 49,990

Term of patent 7 years

To all whom it may concern:

Be it known that I, JAMES H. CANNON, a citizen of the United States, residing at Los Angeles, in the county of Los Angeles and State of California, have invented a new, original, and ornamental Design for a Lamp, of which the following is a specification, reference being had to the accompanying drawing, forming part thereof.

Fig. 1 is a side elevation of a lamp, showing my new design.

Fig. 2 is a plan view of the lamp.

Applicant's lamp embodies a base having an upwardly curved edge, a band encircling substantially the medial portion of the socket and con-

nected to the supporting bar, a cap on the lower end of the socket, the walls of which are upwardly curved, an annular member on the upper end, the lower edge of which is inwardly curved, a ring below the band, the lower edge of which is inwardly curved, a semi-spherical reflecting shield attached to the annular member, and a second semi-spherical shield attached medially to the first-mentioned shield, the second shield having a semi-circular notch provided therein.

I claim:

The ornamental design for a lamp, as shown and described.

JAMES H. CANNON.
